UNITED STATES PATENT OFFICE.

GRIFFITH HUNTER, OF CHICAGO, ILLINOIS, ASSIGNOR TO S. A. HUNTER,
OF SAME PLACE.

APPARATUS FOR HOISTING AND LAYING STONE.

SPECIFICATION forming part of Letters Patent No. 270,675, dated January 16, 1883.

Application filed November 23, 1882. (No model.)

To all whom it may concern:

Be it known that I, GRIFFITH HUNTER, a citizen of the United States, residing in Chicago, in the county of Cook and State of Illinois, have invented a new and useful Improvement in Apparatus for Hoisting and Laying Stone, of which the following is a specification.

The object of the present invention is to provide an apparatus for facilitating the operation of hoisting, moving into place, and laying heavy stones; and to this end my invention consists in a windlass for raising the stone, mounted on a movable frame, which is provided at one end with two pairs of truck-wheels, the inner higher pair of which having a swiveling axle, so that the device may be readily guided when supported on the swiveling truck-wheels, and the outer pair of wheels being adapted to support the frame upon suitable tracks astride the wall wherein the stones are to be laid, the windlass-frame proper being itself adjustable transversely on the truck-frame on which it is supported. The truck-frame is also provided with suitable platforms for the men operating the machine. The rear end of the truck-frame is provided with a swinging derrick, by means of which stones or columns may be laid in the foundations of bridges, or places where it is impracticable to support the truck astride the wall.

In the accompanying drawings, which form a part of this specification, and in which similar letters of reference indicate like parts throughout the several figures, Figure 1 is a side elevation of a device embodying my invention. Fig. 2 is a front end elevation of the same. Fig. 3 is a side elevation, and Fig. 4 is a plan view. In Figs. 1 and 2 the swinging derrick is removed.

In said drawings, A represents the truck-frame, consisting essentially of a pair of longitudinal beams, a a , on each side, between which the outside wheels, B, are hung in suitable bearings, cross-pieces a' , posts a^2 , braces a^3 , brace-rods a^4 , and upper rectangular frame, a^5 . The front end of the truck A is supported upon a pair of truck-wheels, C C, whose axle C' is journaled in a swiveling frame or fifth-wheel, c, which is provided with a tongue, C², for guiding the truck. The windlass-frame D

rests upon this rectangular frame a^5 , and it is provided with small rollers d, so that the frame may be easily moved transversely on the rectangular frame. The transverse pieces of the rectangular frame are provided with racks E 55 E', and the windlass-frame is provided with a shaft, e, a crank, e', for turning the same, and spur-wheels or pinions e², which engage with the racks, whereby the windlass may be moved or adjusted transversely in laying the stones. 60

F represents the windlass, which may be driven by power or by hand through the spur-wheels f f' and crank f².

G represents the block and tackle, which is provided with suitable grappling devices. 65

The racks E E' are secured to the inside of the frame and project slightly above its surface, so that they serve as a guide to the windlass-frame in its transverse motion.

H is a swinging or gallows derrick, having 70 a hinge or loose bearing, h, for the foot of the derrick at the rear end of the truck-frame.

K K are the guy-ropes, which are secured at one end to the top of the derrick, and at the other to the front end of the truck-frame. 75

The windlass-frame, when the derrick is being used, is turned around on the truck-frame in the position shown in Figs. 3 and 4, and secured in place thereon by clamps or stirrups k k, which bind the windlass-frame to the truck-frame. 80

By reason of the inner higher pair of swiveling truck-wheels, which support the front end of the apparatus, except when it is run astride the wall, the apparatus may be easily 85 guided or moved to any place desired. If the stones to be laid happen to be at some distance from the wall, a team of horses may be employed to move the apparatus to and from the approach to the wall. In operation a 90 platform or track for the outside truck-wheels is erected on each side of the wall to support the apparatus. When the apparatus is moved over or astride the wall the inner or swiveling truck-wheels are simply suspended from the 95 apparatus above the wall. In setting the stones the stone is brought into the desired position longitudinally on the wall by moving the truck forward or back on the track, and into position transversely by moving the windlass-frame 100

transversely on the truck-frame by means of the rack and pinion and crank for operating the same.

5 L and L' are platforms on each side of the windlass-frame for the men to stand upon in operating the windlass. The platform L' is hinged to the truck-frame, so as to not interfere with elevating the derrick.

I claim—
10 1. The machine for hoisting and laying stone, consisting of a windlass mounted on a movable frame provided with truck-wheels adapted to run on suitable tracks on each side the wall

wherein the stone are to be laid, and provided also at its forward end with an inner swiveling 15 pair of truck-wheels, substantially as specified.

2. The combination of the truck-frame provided with wheels with the windlass-frame and windlass adjustable transversely on the truck-frame, and the rack and pinion for adjusting the same, substantially as specified. 20

GRIFFITH HUNTER.
